STAPLING METHOD AND DEVICE

Emanuel R. Posnack, Brooklyn, N. Y.

Application March 3, 1937, Serial No. 128,832

9 Claims. (Cl. 1—4)

This invention relates to stapling methods and devices for effecting permanent or temporary closures for containers made of corrugated board and the like, for top and bottom sealing of cartons, for securing together several sheets of paper or other material, and for tacking or similar purposes.

In the several conventional methods of stapling, the most commonly employed staple is that having two prongs or legs, either straight or substantially arcuate, driven into the work by a plunger travelling normal to the plane of the work. Another form of staple, only occasionally employed, is the single-legged or flat wire type the top and bottom of which are clenched by positive deflecting means, such as by a top and bottom anvil —this type of staple also being driven by a plunger moving perpendicular to the surface of the work. Both of these staples involve the use of relatively intricate clenching or deflecting mechanisms—and the staples themselves are generally quite expensive due to the length of the stock and the forming operations required to produce them. It is one of the objects of this invention to overcome these shortcomings by simplifying stapling operations and reducing the cost thereof—an objective which I attain by employing in certain forms of this invention an inclined drive preferably although not exclusively with 25 single-legged staples having the penetrating prongs thereof also inclined with respect to the surface of the work. By means of such a method, a relatively simple and inexpensive staple can readily be driven into the work whereby the material being stapled will be held between the head and leg of the staple to resist a vertical upward pull.

It is also within the contemplation of this invention to enable a straight single-legged staple to be driven into the work simultaneously with the formation of a head thereon whereby the device serves both as a staple forming and driving mechanism. Due to the employment of an inclined drive with a staple moving into the material at an inclination, a collapse of a portion of the top of the staple against the work can be effected when the support for the staple is eliminated or retracted, thereby obviating the necessity of employing special dies or anvils for forming 45 the top head of the staple.

And it is also an object of this invention to employ the principles above mentioned and the methods based thereon either in connection with a flat wire or single-legged type of staple or one 55 having two legs with a connecting cross-bar.

Another object of this invention is to provide a staple whereby a secure operative grip will be effected by employing the method above referred to, and whereby a plurality of staples adapted to be driven thereby can be economically housed in the structure thereof.

It is also within the contemplation of this invention to enable a staple to be clenched or bent within the work without the use of an underlying anvil, an objective which is attained by causing 10 the leg or legs of the staple being driven to be curled into the work due to the engagement thereof with a relatively rigid member positioned above the work, preferably aided by the resistance afforded by the material being stapled.

Another object of this invention is to employ the method above referred to for effecting a stapling operation with the use of an underlying anvil whereby it can be employed particularly 15 for bottom stapling of cartons and for the stapling together of several sheets of paper.

Other objects, features and advantages will appear from the drawing and the description hereinafter given.

In the drawing:

Figure 1 is a fragmentary vertical section of a stapling machine employing an inclined driver and a single-legged staple with an inclined penetrating prong, illustrating the principle of one of the features of my invention.

Figure 2 is a vertical sectional view showing the relative position of the parts of Figure 1 upon the completion of the driving stroke.

Figure 3 is a fragmentary vertical section of a stapling machine employing two inclined drivers, the drive of one being advanced with respect to that of the other.

Figure 4 represents the parts of Figure 3 after the completion of the driving stroke.

Figure 5 is a fragmentary vertical section of a device substantially similar to that shown in Figure 3, the drivers being adapted for simultaneous operation.

Figure 6 represents two staples, one long and one short, driven into the work by a device similar 45 to that of Figure 3.

Figure 7 is a plan view of two staples driven by a device similar to that of Figure 3, the heads of the staples being shown in crossing relation to each other.

Figure 8 represents a modified form of staple driven into the work by a device similar to that of Figure 1, the staple containing an additional vertically disposed short leg.

Figure 9 is a fragmentary vertical section of a 55

stapling device with an inclined plunger shown upon the completion of its stroke after driving a staple having a leg forming an obtuse angle with the head thereof.

5 Figure 10 represents two staples driven by a device similar to that of Figure 3, one of the staples being that shown in Figure 8.

10 Figure 11 represents two staples, one of the form shown in Figure 8, driven by a device similar to that of Figure 3 with the heads thereof in crossing relation.

15 Figure 12 is a modified form of staple driven by the method and device of my invention, the staple being provided with a long and short leg substantially parallel to each other.

20 Figure 13 is still another form of staple, shown driven into the work by the device and method of my invention.

25 Figure 14 is a fragmentary vertical section of another form of stapling machine embodying my invention, including an underlying anvil, the parts being shown during the operative drive of the plunger.

30 Figure 15 is a view similar to Figure 14 showing the staple in its fully clenched position.

35 In the operation of a preferred form of my invention, an inclined staple is driven downwardly into the work by an inclined plunger whereby, upon the completion of the stroke, the head portion of the staple will engage the surface of the work and the penetrating portion thereof will be inclined at an angle thereto. Hence in this position the head and penetrating portions of the staple will hold therebetween a portion of the material being stapled, thereby resulting in a resistance to a straight upward vertical pull of the staple.

40 Thus in Figures 1 and 2, which illustrate the principle of one of the features of this invention, the staple 30, positioned against and supported by the inclined guide 31, is driven downwardly by the inclined plunger 32. Inasmuch as the leg 33 of the staple is inclined with respect to the surface of the work 34, and the head 35 of the staple is substantially parallel to said surface, a downward drive of the plunger will cause said head to engage the surface of the work, and upon continued pressure, to be actually countersunk therein as shown in Figure 2. The leg 33 enters at an inclination, substantially in the direction shown in Figure 2, assuming that the resistance afforded by the material is not sufficiently great to cause an additional bending of said leg. Hence it is apparent that the portion 36 of the material being stapled is partially gripped between the head and leg of the staple, thereby presenting a resistance against a straight upward vertical pull.

45 When the staple is actually operatively embedded within the work, the only visible portion is the exposed head thereof, there being nothing to indicate the direction in which the leg extends. In attempting to remove the staple, the normal tendency would obviously be to pull vertically upwardly. This would be resisted by all the material directly above the inclined leg 33 of the staple. In addition to this resistance, there is of course the usual frictional resistance of the material against the leg of the staple, thereby necessitating more than an average pull to dislodge the staple, unless it is pulled outwardly in the direction of the leg thereof.

50 Although a single staple of the type shown in Figures 1 and 2 may be sufficient in many cases especially for tacking and tagging purposes, a

more effective stapling result can be obtained by coactively driving two staples into cooperative relation into the work, particularly as illustrated in Figures 3 and 4. Here there are two plungers 55 and 56 movable within the channels 40 and 41 respectively, these channels being inclined with respect to the base 43 of the structure and forming therebetween an angle substantially equal to the angle between the head and leg portions of the staples. The walls of said channels obviously serve as guides to direct the said plungers 55 and 56 downwardly along converging paths, into the outlet or open portion 44 in the base of the machine. It is obvious that the plungers 55 and 56 can be operatively actuated by any conventional means whereby they can be made to follow the convergent paths of said channels. Under the influence of said plungers, the staples will become embedded in the work, the terminals of the inclined legs of the two oppositely positioned staples being brought into proximate relation to each other.

55 It will be seen from an examination particularly of Figures 3, 4 and 6 that the heads of the staples are substantially in one vertical plane, as is most obvious from an inspection of Figures 4 and 6 which illustrate the heads of the staples as being in engaging relationship at the termination of the drive. And it is of course obvious that the ultimate relative positions of the heads of cooperating staples will be dependent upon the angles and relative positioning of said channels. In the particular form of my invention illustrated in Figures 3 and 4 the opening 44 is shown sufficiently wide to accommodate both heads in overlapping relation as well as the terminal portions of the plungers 55 and 56. In the form shown, the plunger 56 is relatively narrow and adapted only to engage that portion of the underlying staple 58 adjacent the junction of the head and leg thereof, whereas the plunger 55 is considerably wider and is in engagement with substantially the entire head portion of the underlying staple 57.

60 It is of course understood that the relative dimensions of the plungers are merely illustrative and that other dimensional proportions may be employed within the spirit and scope of this invention.

65 In the form of my invention illustrated in Figure 3 it is preferred that the plunger 56 be actuated slightly before 55, so as to enable the staple 58 to be completely embedded within the work before staple 57, thereby enabling the overlapping relationship of the heads to be effectuated. As is clearly illustrated in the drawing, the opening 44 is sufficiently wide to accommodate not only the overlapped heads of the staples, but also the lower extremities of the plungers 55 and 56, thereby rendering it readily feasible for the combined drive to be effectuated. In the form 70 illustrated a considerable portion of the drive of both plungers takes place simultaneously. The said plungers 55 and 56 can be actuated in any conventional manner, as it is primarily within the contemplation of this invention to provide such means and such steps whereby two of the above-described type of staples can be operatively driven by any selected or conventional actuating means.

75 With this arrangement, the staple 58 can obviously not be withdrawn due to the fact that the head thereof is overlapped by the head of staple 57; and the staple 57 can only be withdrawn by a pull in the direction of the leg 57, inasmuch as a straight vertical upward pull will be resisted 75

by the material above the inclined leg. It is of course obvious that by means of the device of Figure 3 it is possible that the heads of the staple can also be in crossing relation, as is shown in Figure 7, where the underlying staple 59 is held against withdrawal by the overlying staple 60.

In Figure 5 the relative positions of the plungers 37 and 38 are such as to bring the heads 52 and 53 of the staples 47 and 48 into proximate relationship, as distinguished from the overlapping arrangement above described. In this form of my invention, the drive of both staples can be completed simultaneously.

By using the method employed by the structures of Figures 3 and 4, but with the first driven staple shorter than the other, a result such as is shown in Figure 6 can be obtained. Here the two staples are preferably driven in the same plane, the head of the first driven staple 61 underlying that of the second drive staple 62, the terminal point 63 of the first driven staple being positioned above the leg of staple 62. In this structure it is of course obvious that the plungers 64 and 65 are operatively actuated similar to the plungers 55 and 56 of Figures 3 and 4. When the staples are embedded in position as shown in Figure 6, a straight upward pull of staple 62 will be resisted not only by the material above the leg thereof, but also by the leg 61 which is in the path thereof; and the staple 61 could obviously not be withdrawn because the head thereof is overlapped by the head of staple 62. With this arrangement, not only are two staples driven into the work to coact with each other in a minimum space to effect a secure stapling grip, but they are so arranged as to make it extremely difficult to remove them without plowing through the material of the work.

It is preferred that the two oppositely positioned staples such as 57 and 58 be in the same vertical plane, inasmuch as it is highly probable that the ultimate positions of the legs of the staples would be as shown in Figure 4. In actual practice, even though the legs of the two staples are in substantially the same plane, one will normally slip by the other to complete the clench in crossing relationship.

By employing the inclined drives shown in any of the foregoing structures, modified forms of staples can also be driven to produce greater holding effects. For example, the staple 66 of Figure 8 contains a downwardly extending short leg 67, so that the holding power of the staple will be increased considerably thereby. When two plungers are employed, one of the legs 68 (see Figure 10), may also contain such a short downwardly extending leg, and the head of staple 69 may be substantially flat. When the staples are driven in crossing relation to each other, the result will be similar to that shown in Figure 11, where the staple 70 contains a short downwardly extending leg and the underlying staple is preferably substantially flat headed.

It is within the contemplation of this invention to employ a leg forming either an acute or an obtuse angle with the head thereof, the staple 66a of Figure 9 showing the obtuse angle arrangement, whereas the other of the illustrated staples are of the acute angle type.

The short additional head above referred to may extend vertically downwardly as shown in Figure 8, or may be parallel to the long leg as is shown in Figure 12 where the short leg 71 is parallel to the leg 72. The short leg 73 of Figure 13 may be bent inwardly by preforming it in

that direction; and there may be a further inward bending thereof as a result of the resistance of the material 74 upon the completion of the drive by any of the structures above described.

With any of the forms of staples shown in Figures 8 to 13 inclusive, where a short leg depends from the head of the staple on the side thereof opposite the long leg, a very secure clenching effect will be obtained. With any of these staples, a straight vertical upward pull will be resisted by the material directly above the inclined long leg; and a pull in the direction of the inclination of the long leg will be resisted by the material adjacent the short leg. Thus, by referring to Figure 8, a pull in the direction of the arrow will be resisted by the portion 79 of the material being stapled, inasmuch as the short leg 69 would have to plow through said portion 79 in order to enable the staple to be removed; and a straight vertical pull will be resisted by the material above the long leg. Hence regardless of the direction of the pull, the staple will be firmly held in place.

In connection with the aforementioned staples containing short legs, it should be noted that they can be readily driven by any of the inclined drives above described. The major portion of the drive is employed to direct the long leg into the material substantially in the direction of the inclination of this leg; and the short leg will begin to penetrate the staple only towards the very end of the plunger stroke. There can be no plowing through to any appreciable extent, particularly in view of the fact that both the staple and the material being stapled are intended for this purpose to be slightly resilient and sufficiently tough.

Employing the principle of an inclined drive, an underlying anvil 75 can be employed where that may be necessary, such as for bottom stapling of containers, or for the securing together of several sheets of paper. By referring to Figures 14 and 15, it will be seen that the inclined plunger 76 engages the staple 77 to direct it through the work against the said anvil 75, the position of the anvil being such as to receive the penetrating portion of the leg of said staple 77. Upon the completion of the stroke as shown in Figure 15, the staple will be clenched both on top and bottom, thereby clamping the material therebetween.

In this form of stapling device, a relatively inexpensive staple can hence be employed to perform the stapling operations generally performed by conventional office stapling machines or bottom staplers for cartons. One of the advantages of having the leg of the staple enter at an angle is that the clenched bottom portion of the staple can readily be made to extend beyond the terminal point 78 of the head of the staple thereby providing a secure clench over an extended area with a relatively short and inexpensive staple.

It is of course understood that other additional forms and modifications of the apparatus and adaptations of the method constituting this invention can be employed beyond and in addition to those hereinbefore described, all within the scope of the appended claims.

What I claim is:

1. In a stapling machine for driving two oppositely positioned staples each having a head portion substantially parallel to the surface of the work being stapled and a leg at an inclination thereto, two plungers converging towards the base of the machine and each engageable with one of said staples, the inclination of the plungers

- being substantially that of the legs of the corresponding staples, an opening in the base of the machine sufficiently wide to accommodate the head portions of said two oppositely positioned staples when in overlapping engagement and the lower portions of the two plungers at the end of their strokes, and guiding means for directing said plungers and the staples driven thereby to said opening whereby the said head portions are in overlapping engagement.
2. In a method of driving staples each having a head and a leg forming an acute angle therewith, the steps of positioning two oppositely disposed staples with their legs in converging relation and their heads in substantially one vertical plane, applying driving pressure upon the heads of said oppositely disposed staples in the direction of the work being stapled, and directing said staples in such converging paths toward the work as to cause the heads of the two driven staples to overlap and the legs thereof to penetrate said work in crossing relation to each other.
3. In a method of driving staples each having a head and a leg forming an acute angle therewith, the steps of positioning two oppositely disposed staples with their legs in converging relation and the head of one closer to the work being stapled than the other, the heads of the two staples being substantially in one vertical plane, applying driving pressure first upon the head of the lower staple and then upon the other staple in the direction of the work, and directing said staples towards the work at such inclination as to cause the legs of the two staples to penetrate the work and the heads thereof to be in overlapping engagement.
4. In a method of stapling, the steps of selecting two staples each having a head and a leg forming an acute angle therewith, the leg of one of the staples being shorter than the other, positioning the two staples with their legs converging towards the work being stapled, applying driving pressure first upon the head of the shorter-legged staple and then upon that of the other staple in the direction of the work, and directing said staples towards the work at such an inclination as to cause the legs of the two staples to penetrate the work and the heads thereof to be in overlapping engagement.
5. In a method of stapling, the steps of selecting two staples each having a head and a leg forming an acute angle therewith, the leg of one of the staples being shorter than the other, positioning the two staples in substantially the same plane with their legs converging towards the work being stapled, applying driving pressure first upon the head of the shorter-legged staple and then upon that of the other staple in the direction of the work, and directing said staples towards the work at such an inclination as to cause the legs of the two staples to penetrate the work and the heads thereof to be in overlapping engagement, and whereby the driven legs will be in substantially the same plane.
6. In a stapling machine for driving two oppositely positioned staples each having a head portion substantially parallel to the surface of the work being stapled and a leg at an inclina-

tion thereto, two channels converging towards the base of the machine and each inclined thereto at an angle substantially equal to that between the leg of each staple and its head, said channels being adapted to slidably accommodate two oppositely disposed staples with the heads thereof in substantially one vertical plane, two plungers slidably movable within said channels and each operatively engageable with the staple therein, said channels extending through the base of the machine and thereby providing an open part for operatively accommodating the head portions of the staples.

7. In a stapling machine for driving two oppositely positioned staples each having a head portion substantially parallel to the surface of the work being stapled and a leg at an inclination thereto, two channels converging towards the base of the machine and each inclined thereto at an angle substantially equal to that between the leg of each staple and its head, said channels being adapted to slidably accommodate two oppositely disposed staples with the heads thereof in substantially one vertical plane, two plungers slidably movable within said channels and each operatively engageable with the staple therein, one of said plungers being engageable with substantially the entire head of the underlying staple and the other plunger being engageable with that portion of the head of its underlying staple adjacent its juncture with the leg of the staple.

8. In a method of driving staples, the steps of selecting a staple of resilient wire comprising a substantially flat head portion with a long and a short leg at opposite sides thereof, the long leg being inclined to the head portion and the short leg being in non-parallel relation to the long leg, positioning the staple with said head portion substantially parallel to the plane of the work being stapled and said legs extending towards the work, applying driving pressure upon said head portion of the staple, and directing the staple towards the work in a path substantially in the direction of the said inclination of the long leg to force said legs into the work, whereby the short leg will encounter greater resistance to penetration than the long leg resulting in a yieldable deflection thereof within the work.

9. In a method of driving a staple of resilient wire with a substantially flat head portion and non-parallel long and short legs at opposite sides thereof, the long leg being inclined to the head portion at an acute angle, and the short leg forming an angle with the head portion no greater than 90°, the steps of positioning the staple with said head portion substantially parallel to the plane of the work being stapled and said legs extending towards the work, applying driving pressure upon said head portion of the staple, and directing the staple towards the work in a path substantially in the direction of the said inclination of the long leg to force said legs into the work, whereby the short leg will encounter greater resistance to penetration than the long leg resulting in a yieldable deflection thereof within the work towards the long leg.

EMANUEL R. POSNACK.
